UNITED STATES PATENT OFFICE

VINCENT SCHOBBENS, OF ANTWERP, BELGIUM

CARBURETOR

Application filed August 26, 1927, Serial No. 215,699, and in Belgium August 26, 1926.

Applications for patent have been made in the following countries: Belgium, August 26th, 1926; Belgium, December 21st, 1926; Belgium, January 14th, 1927; France, September 6th, 1926; Germany, September 8th, 1926; Belgian Congo, March 7th, 1927.

This invention relates to improvements in carburetors, the object being to provide an improved carburetor, adapted to supply an explosive mixture to internal-combustion engines particularly automobile-engines, comprising either a mixture of combustion-gas with air or of liquid fuel with air.

In order to produce the desired results, use is made of a principal body, of an admission chamber for the combustion gas under pressure, of a float-chamber for the liquid-fuel supply, and of an atmospheric air intake chamber.

Moreover, the apparatus comprises a slow-speed spray-nozzle both for gas and liquid fuel, and a main spray-nozzle, comprising a nozzle for the gas and a spray-nozzle for the liquid fuel.

Means are provided whereby to establish communication of the slow-running or spray-nozzle alternatively with the combustion-gas admission chamber or with the float-chamber of the liquid fuel. Other means are provided for the same purpose for the main nozzle. Moreover, means are provided whereby to control the output of the spray-nozzles and to establish an automatic and controllable air supply, proportional to the output of the said spray-nozzles; and, means are also provided to produce an automatic shutting of the combustion-gas inlet to the main spray-nozzle when the engine is stopped.

A practical embodiment of the invention is represented in the accompanying drawings, forming a part of this specification, in which similar characters of reference indicate corresponding parts in all the views.

Figure 1 is a partially sectional elevation view, looking in the direction of the arrows 1-1 of Fig. 2, the various elements being shown in full gas supply position, and the apparatus being arranged to utilize one or the other of the above-mentioned fuels.

Fig. 2 is a partially-sectional end view, looking in the direction of the arrows 2-2 of Fig. 1.

Referring to the drawings the apparatus is composed of a main body 3, having an attachment flange 4, a throttle valve 5 is located in the tubular part of the main body. A slow-running device is arranged between the throttle-valve and the admission pipe to the cylinders, which device comprises a spray-nozzle 6 provided with a control-needle 6', the said nozzle having orifices 7 for fuel-admission, and communicating with an annular groove 7'. The nozzle 6 is screwed into a supporting socket 8 connected to the main body and provided with an aperture 9 for the fuel passage.

A sleeve 10, fixed by means of a nut 10', surrounds the socket 8, and has a pipe connection 11 which is provided with a three-way valve 12. The sleeve has a transverse passage 13 communicating with the annular groove 7' of the nozzle 6. The socket 8 is connected to the main body by a coupling 14 which has air intake side apertures 15, the passage-section of which is controllable by means of a ring 16 provided with apertures 17, corresponding to the orifices 15.

Above the spray nozzle 6 is located a shutting device 18, comprising a rubber-patch 19 and presenting lateral orifices 20 for the passage of the gas. Moreover a diffusing cap 21 having lateral orifices 22 is arranged between the shutting device 18 and the inlet conduit to the motor.

A stem 23 subdued to the action of a spring 24 in a housing 25, bears downwardly against the shutting device 18. The upper extremity of the stem is guided in the housing 25, while its lower extremity is guided by an opening 90 in the spray-cap 21.

In the main body 3 and in advance of the throttle 5 is arranged the main supply device, comprising a nozzle 26 surrounding a nozzle 27 for the liquid fuel.

The main nozzle 27 communicates at its base with a pipe 28 (Fig. 2) united with the float-chamber 29 for the liquid fuel, the latter communicating with the slow-running 100

nozzle 6 through a pipe 30 issuing into the three-way valve 12.

The pipe 26 and the nozzle 27 may be closed by an obturator 31 subdued to the action of a spring 32. A stem 33 carrying the obturator 31, is provided at its upper part with a head 34 actuated by a cam 35, mounted on an arm 36 which is secured to axle 5' of the throttle 5.

10 On the extremity of the main body 3 a chamber 37 is arranged, having an opening 38 communicating with the atmosphere and provided with a closing flap 39 united with an arm 41 which is secured to an oscillating 15 axle 42 by means of a cable 43 which is guided on a pulley 44.

An admission chamber 45 for the gas under pressure communicates with the main and slow-running nozzles respectively through the 20 conduits 46 and 47. This chamber 45 is provided with an admission orifice 48 which may be completely or partially closed by means of a closing device 49, operable by a handle (not shown) or the like.

25 In the interior of the chamber 45 is located a diaphragm 51, in the center of which is mounted a stop 52, against which a stem 53 abuts. Said stem slides in a guide 54, mounted on the cover 55, the position of the stem 30 on the cover being variable. The upper end of the stem 53 is in contact with a cranked lever 56, subdued to the displacements of a finger 57, located on the extremity of the shaft 42 and eccentric to the latter.

35 The stop 52 is also in contact with the lever 58, articulated at 59 and provided with a lateral finger 60. Said finger bears against a pin 61 of a piston 62, which is movable in the guide 63 and is subdued to the action of 40 a resisting spring 64, the said piston moving in the axial direction of the orifice 65 of the gas-outlet to the conduit 46 and the nozzle 26.

When combustion gas under pressure is 45 utilized, the operation of the apparatus is as follows.

The engine being stopped, the three-way cock 12 is put in the position shown in the drawings, so as to connect the slow-running 50 nozzle 6 with the gas-admission chamber 45. The gas being not yet admitted to the latter, the piston 62, under the stress of the spring 64, is displaced axially and closes the orifice 65, connecting with the main spray-nozzle 26. In this displacement of the piston 62 the diaphragm 51 is lifted, and hence the closing flap 39 is brought to the position, in 55 which it closes the window 38, by means of the action of the stem 53 of the lever 56, 60 of the finger 57 and of the arm 41, on the shaft 42.

After the opening of the tank located on the vehicle and containing the combustion gas, the closing device 49 is removed so as to 65 allow the admission of gas to the chamber

45 through the aperture 48. From the chamber 45 the combustion-gas may freely come to the slow-running nozzle 6, passing through the conduit 47 and the three-way cock 12. The motor, being now set in motion creates an under-pressure, behind the throttle 5, which will cause, by lifting the stem 23 against the pressure of the spring 24, the lifting of the closing device 18, the rubber patch 19 of which will open the nozzle 6, 70 which will allow the combustion-gas, issuing from this spray-nozzle, and already mixed with air, admitted through the apertures 15 to flow into the aspiration piping of the motor through the apertures 20 of the said closing device, and through the apertures 22 of the cap 21.

When, by means of the gas-controlling device, the throttle 5 is acted upon in order to produce acceleration of the motor, the rotary movement, applied for this purpose to the handle 66 will displace also the cam 35 mounted on the arm 36, fixed on the axle 5' of the throttle 5. In its displacement the cam 35 will correspondingly lift the head 34, 80 as well as the closing device 31 against the action of the spring 32, and the issue of the main spray-nozzle 26 will be thus opened more or less, following the angular displacement of the arm 36.

The throttle 5 being rotated at a certain angle, the vacuum will be produced also before the same as well as in the compartment 37, closed by the flap 39. The latter, under the influence of the aspiration will be displaced to the interior and will open the window 38 in order to aspire the atmospheric air correspondingly to the degree of the opening of the throttle 5.

Because of its movement the shutting flap 39 will draw the cable 43 fixed to the end of the arm 41, which will shift the shaft 42 and the finger 57 eccentrically mounted on the end of the latter. The finger 57 will be thus lowered and will lean on the cranked lever 56 in order to lower the stem 53 and consequently to lower the stop 52 on the diaphragm 51. In its lowering movement the stop 52, which is in contact with the lever 58, lowers the latter, which by means of its lateral finger 60 axially displaces the piston 62 by means of the pin 61, in order to open the orifice 65 of the gas passage to the main nozzle 26. It is obvious that under these conditions, during the running of the motor, the output of the combustion-gas through the nozzle 26 and the atmospheric air admission through the opening 38 will be proportional to the degree of opening of the throttle 5.

When the engine is stopped, all vacuum production ceasing in the body of the carburetor and in the chamber of aspiration of air 37, the closing flap 39 will be drawn to the position required to close the opening 38, by the spring 64 in the gas admission 120

chamber 45, inversely to what occurs when the motor is set in motion, the said spring 64 pushing back the piston 62 to the position for closing of the aperture 65. In the same 5 way the closing device 18, under the action of the pressure, acting upon the stem 23 by the spring 24 will be driven back to the position for closing the slow-running nozzle 6. In this closing position of the closing device 10 18 the apertures 15 and the orifices 20 are completely closed.

When the apparatus is to be run with liquid fuel, the aperture 48 is carefully closed by means of the plug 49 and the three-way 15 valve is put in the position, required to establish communication between the slow-running nozzle 6 and the float chamber 29.

The liquid fuel after being admitted into the float-chamber 29, reaches the main spray 20 27 by way of the conduit 28 and reaches the slow-running nozzle through the three-way valve 12. The motor being not yet set in motion the two nozzles are covered by the shutting devices 18 and 31 respectively.

25 When the engine is set in motion the closing device 18 is lifted as before in order to allow the gaseous mixture formed by the liquid fuel from the nozzle 6 and by the air, admitted through the apertures 15, to get 30 access to the intake piping of the engine.

The next operation of the handle 66 in order to actuate the throttle 5 will cause the displacement of the cam 35 which is fast with the arm 36 and will lift the plug 31 which 35 uncovers the outflow orifice of the nozzle 27. The movement of the throttle 5 will produce the same action as before to draw the closing flap 39 and to allow intake of the atmospheric air in appropriate quantity, so as to produce 40 a good mixture of the liquid fuel, flowing out of the nozzle 27.

If no further utilization of liquid fuel is desired, the access of the same to the float-chamber 29 is closed, and the three-way valve 45 is again put in the position required for the use of the combustion-gas. Moreover, existing means permit the emptying of the float-chamber 29 in order to avoid all undesired mixing of the liquid fuel, which might 50 remain eventually with the combustion-gas.

What I claim is:

1. In a carburetor adapted to use alternately liquid fuel and combustion gas under pressure for preparing an explosive mixture, 55 in combination a main hollow body, a throttle in said body, a slow running spray nozzle, means to automatically regulate the output from said nozzle, a main nozzle for supplying combustion gas or liquid fuel respectively, 60 means to automatically control the output of said main nozzle in proportion to the degree of opening of the throttle, an atmospheric air intake chamber in communication with said hollow body, means to automatically control 65 the air intake to said intake chamber, an ad-

mission or expansion gas chamber in communication with said main nozzle, and provided with means to automatically close, open and control the output of said chamber to the main nozzle, the control means in said expansion chamber being connected to the control means of the air intake chamber, and means to permit gas or liquid fuel to be utilized at will. 70

2. A carburetor as claimed in claim 1, including a chamber having cross sectionally variable air inlet openings in which chamber said slow running nozzle is arranged and also including a bell shaped obturator at the discharge end of said nozzle and in said chamber and provided with mixed gas outlet apertures, and yieldable means active to normally close said obturator and to permit the opening thereof by the suction of the engine. 75

3. A carburetor as claimed in claim 1, in which the said means for automatically controlling the output of said main nozzle include a spring active to normally close said main nozzle and means with which the throttle valve and the obturator are provided to cause said obturator to be moved to open position correspondingly with the opening of such valve to such position. 80

4. A carburetor as claimed in claim 1, in which the means for automatically controlling the air intake into the air intake chamber comprise an opening and a closure for said opening, said closure being arranged to be moved to open position by the suction of the engine and also including means to regulate the intake of gas by the combustion gas chamber and means actuated by said air intake valve to cause the same to also actuate the means for controlling the intake of gas by the combustion gas chamber. 85

5. A carburetor as claimed in claim 1, in which the air intake chamber is provided with an opening and a closure for said opening, said closure being operated by the suction of the engine and the displacement of the closure being effective in actuating the means for controlling the intake of gas to the expansion gas chamber, said means comprising gas pressure actuated means in said expansion gas chamber, a lever to move said gas pressure actuated element against the pressure of gas in said expansion gas chamber, a rock shaft connected to said air intake controlling valve and a finger movable by said shaft and arranged to actuate said lever. 100

In witness whereof I affix my signature.

VINCENT SCHORBENS.
